UNITED STATES PATENT OFFICE.

MARTIN P. BOSS, OF OAKLAND, CALIFORNIA.

FRICITION-CLUTCH.

SPECIFICATION forming part of Letters Patent No. 325,388, dated September 1, 1885.

Application filed July 1, 1885. (No model.)

To all whom it may concern:

Be it known that I, MARTIN P. BOSS, of the city of Oakland, Alameda county, State of California, have invented an Improvement in 5 Friction-Clutches; and I hereby declare the following to be a full, clear, and exact description of the same.

My invention relates to the class of friction-clutches; and my invention consists, first, in 10 a ring of a springy nature secured to the part or mechanism to which power is to be transmitted and operated by frictional mechanism on the driving-shaft, and, secondly, in the novel frictional mechanism and the means for 15 operating it, hereinafter described.

The general object of my invention is to provide a simple and effective friction-clutch. The particular objects I shall explain in the course of the following description.

20 Referring to the accompanying drawings, Figure 1 is a perspective view of my friction-clutch, a portion of the friction-ring and gear being broken away. Fig. 2 is a vertical section through one-half of the clutch. Fig. 3 is 25 an elevation of the head D and guides E. Fig. 4 is a side view of one of the shoes F. Fig. 5 is a view of the yoke G.

Though the clutch may be used to drive pulleys, &c., I here show a gear, A, loose on 30 the driving-shaft B. The gear is formed with a small flange, a, to which is secured by means of pins c the ring C. This ring is made of metal, generally cast-iron, and is of a springy nature, having a suitable diameter and a thinness adapted to this end. The pins c are not seated tightly in the flange of the gear, but enter holes therein slightly larger in diameter, so that the spring of the ring may not be interfered with, and it may be allowed to accommodate itself to any irregularity in the adjustment of the shoes.

40 D is a head having somewhat of an H shape, with a wide cross-bar, which is bored out to receive the driving-shaft B, to which the head 45 is fixed by set-screws d. Through the sides of the head longitudinally pass the guides E, consisting of round iron. These are fixed therein in suitable manner, a practical construction being to cast the head around them.

50 The ends of the guides E project beyond the head, and on them are fitted the shoes F, which

are adapted to slide to and from the head. The shoes are provided with a facing, f, the outer surface having the curvature of the ring C, against which they are adapted to bind 55 when forced outwardly.

In the sides of the cross-bar of the H-shaped head D are made recesses d', in which the arms g of the yoke G loosely fit. The yoke G has a hub, g', which is loosely mounted on the 60 shaft B, and is provided with a peripheral groove, g'', for a loose collar, I. The arms of the yoke fitting in the recesses of the head, the yoke itself is caused to rotate with the shaft. Mounted in a bed-timber is a rock-shaft, J, 65 actuated by a hand-lever, K. On the shaft are cranks j, from the ends of which extend links j' to the collar I on the hub of the yoke. By operating lever K the yoke may be moved longitudinally on the shaft B, its arms being 70 fitted loosely in the head D.

75 L are toggles or links, one end of which is pivoted in the shoes F on a pin, l, and the other end is pivoted in the ends of the yoke-arms by pins l'. When the yoke is moved toward the head D, the toggles force the shoes outwardly against the ring C, and when moved back from the head the toggles withdraw the shoes.

80 The peculiar construction of the toggles is shown in Fig. 2. It consists of the heads m, into one of which an adjusting screw-bolt, m', is let. The head of this bolt abuts against the opposite head, m, and is connected therewith by a swivel-joint formed by a pin, m'', through 85 said head into the head of the bolt, and a cross-pin, m'', holding the pin m'' in place. This permits the bolt to be turned to shorten or lengthen the toggles. A jam-nut, m', fixes the bolt. 90

95 The operation of the clutch is as follows: When the shoes are withdrawn from the ring C, the gear A remains stationary, it being loose on the shaft. When the clutch is to be thrown in, the lever K is operated to rock shaft J in a direction to force the yoke G toward the head D. The arms of the yoke being pivoted to the lower ends of toggles L, its motion parallel with the shaft is transferred through the toggles into motion at right angles to said 100 shaft, thereby forcing the shoes F outwardly. These, sliding accurately on the guides E, bind

against the ring C, through which power is transmitted to the gear. To stop the gear the operation is reversed.

The object in making the friction-ring C so that it will have a slight spring is not only that it may accommodate itself to an irregular or inaccurate adjustment of the shoes, if such should take place, but also to avoid the necessity of such a delicate adjustment as would be required for a stiff or rigid ring.

The shoes, when forced against a stiff ring, have to be very delicately adjusted, and though binding for a while, may from some cause be relieved slightly, whereupon the ring will slip; but a springy ring, by being forced to a slight elongation, cannot so slip, and the friction will remain perfect. This springy ring I deem of prime importance in a friction-clutch, and I herein claim it, whether used in connection with the friction mechanism described or with other friction mechanisms, and at the same time claiming the particular friction mechanism, whether used with a ring of a springy nature or a stiff ring.

I am aware that friction-clutches are known in which shoes are forced outwardly against a friction-surface by means of toggles, and I do not therefore claim such broadly.

Having thus described my invention, what I claim as new, and desire to secure by Letters Patent, is—

1. In a friction-clutch, the ring C, of a springy nature, secured to the part or mechanism driven and operated by friction mechanism on the part driving, the said friction mechanism bearing directly against the flange of the ring, substantially as herein described.

2. In a friction-clutch, the ring C, of a springy nature, secured to the part or mechanism driven, in combination with radially-moving shoes on the part driving adapted to bind against the ring, substantially as herein described.

3. In a friction-clutch, the ring C, of a springy nature, secured to the part or mechanism driven, and adapted to have a slight movement thereon, said ring being operated by friction mechanism on the part driving, substantially as herein described.

4. In a friction-clutch, the gear A, or other part or mechanism to which power is to be transmitted, having a flange, a, in combination with the ring C, of a springy nature, and operated by friction mechanism on the driving-shaft, and the pins c, through the ring and loosely seated in the flange, whereby the ring may have a slight movement thereon, substantially as herein described.

5. In a friction-clutch, the gear A, or other

part or mechanism to which power is to be transmitted, having a flange, a, and the ring C, of a springy nature, secured to the flange a by pins c, loosely seated thereon, as described, in combination with radially-moving shoes on the driving-shaft adapted to bend against the ring, substantially as herein described.

6. In a friction-clutch, the ring C, of a springy nature, secured to the part or mechanism to which power is to be transmitted, in combination with a head on the driving-shaft, guides in the head, shoes on the guides adapted to move radially to bind on the ring, and mechanism for operating the shoes, substantially as herein described.

7. In a friction-clutch, and in combination with a friction-ring on the part or mechanism to which power is to be transmitted, the head D, fixed on the driving-shaft, the radial guides E, fixed in the head, the shoes F, fitted and sliding on the guides, and mechanism for moving said shoes to force them against or withdraw them from the friction-ring, substantially as herein described.

8. In a friction-clutch, and in combination with a friction-ring on the part or mechanism to which power is to be transmitted, the head D, fixed on the driving-shaft, the radial guides E, fixed in the head, the shoes F, fitted and sliding on the guides, the yoke G, mounted loosely on the driving-shaft and having arms g resting in recesses in the head, the toggles or links L, pivoted to the shoes and to the arms of the yoke, and mechanism for longitudinally moving the yoke to move the shoes radially to or from the friction-ring, substantially as herein described.

9. In a friction-clutch, and in combination with a friction-ring on the part or mechanism to which power is to be transmitted, the head D, fixed on the driving-shaft, the radial guides E, fixed in the head, the shoes F, fitted and sliding on the guides, the yoke G, mounted loosely on the driving-shaft and having arms g resting in recesses in the head, the toggles or links L, pivoted to the shoes and to the arms of the yoke, the collar I, loosely embracing the hub of the yoke, the rock-shaft J, and the links j', connecting the cranks with the collar, all arranged and adapted to operate substantially as herein described.

In witness whereof I have hereunto set my hand.

MARTIN P. BOSS.
